US00D949618S

(12) **United States Design Patent** (10) **Patent No.:** **US D949,618 S**
(45) **Date of Patent:** **** Apr. 26, 2022**

(54) **COFFEE MAKER**

(71) Applicant: **PI-Design AG**, Triengen (CH)
(72) Inventor: **Jorgen Bodum**, Meggen (CH)
(73) Assignee: **PI-DESIGN AG**, Triengen (CH)
(**) Term: **15 Years**
(21) Appl. No.: **29/730,469**
(22) Filed: **Apr. 3, 2020**
(30) **Foreign Application Priority Data**

Dec. 16, 2019 (WO) WIPO90253

(57) **CLAIM**

The ornamental design for a coffee maker, as shown and described.

DESCRIPTION

FIG. 1 is a perspective view of a coffee maker showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the coffee maker that form no part of the claimed design.

1 Claim, 7 Drawing Sheets
